2 Claims. (Cl. 13—31)

This invention relates to melting of gas-containing metal particles of large surface area such as metal powders, sponge, scrap and the like, and particularly to a furnace for melting such gas-containing metal particles to produce gas-free metal ingots.

A principal object of the present invention is to provide a furnace for melting gas-containing metal particles to produce gas-free metal ingots of extreme purity.

Another object of the invention is to provide a furnace of the above type which is simple to operate and is relatively cheap to construct.

Still another object of the invention is to provide a furnace of the above type which provides excellent control of the melting rate to insure complete degassing of the metal.

Still another object of the invention is to provide a furnace of the above type which permits a relatively high rate of melting with the requisite high vacuum.

These and other objects of the invention will in part be obvious and will in part appear hereinafter.

The invention accordingly comprises the apparatus possessing the construction, combination or elements and arrangement of parts which are exemplified in the following detailed disclosure, and the scope of the application of which will be indicated in the claims.

For a fuller understanding of the nature and objects of the invention, reference should be had to the following detailed description taken in connection with the accompanying drawing which is a diagrammatic, schematic, sectional view of a preferred embodiment of the invention.

In the present invention electron bombardment of the metal particles in a cold mold is employed for melting the metal under high vacuum to produce a gas-free metal. In the degassification of metals, it is not essential that the absolute pressure be lower than about 1 to 10 microns Hg abs. It is desired that the metal be heated sufficiently to drive out dissolved and combined gases and volatilize metallic and other impurities. In the micron range of pressures the oxides and nitrides of many metals are either volatile or unstable at the melting point of the metal. Operating an arc-melting furnace at such pressures is extremely difficult unless the arc is between a consumable electrode and a bath of the metal being melted. The very nature of the consumable electrode melting operation, however, makes it extremely difficult to control the melting rate. As a general proposition, the melting operation, with a consumable electrode, is too rapid for complete degassification in a single melting operation. Accordingly, it has become the practice in the industry to double or triple melt metals which are to be of ultimate purity.

While there have been suggestions in the art of small scale melting of metals by electron bombardment of the metal to be melted, this has not been very practical because of the fact that the source of electrons must be maintained at an extremely high vacuum, on the order of a few hundredths of a micron absolute pressure. This means that all of the gas liberated from the metal must be pumped out of the system at this extremely high vacuum. This requires large, expensive high vacuum diffusion pumps. Since the number of diffusion pumps that can be attached to a given furnace is limited by the size of the furnace, and since any diffusion pump has only a definite maximum capacity, the melting rate is limited to

2

the available pumping capacity. This has drastically limited the utility of electron melting to small scale laboratory equipment or to larger systems with expensive extremely high pumping capacities.

The present invention can best be understood by reference to the single figure of the drawing which is a diagrammatic, schematic sectional view of one preferred embodiment of the invention. The furnace includes a vacuum tight chamber 10 having a cold mold 12 which permits maintenance of a small pool 14 of molten metal without contamination of the metal, since the interface between the mold and the metal is maintained solid. The furnace chamber is provided with a high capacity vacuum pump 16, such as a mechanical blower or diffusion pump which can handle large volumes of gases in the 1 to 10 micron pressure range. While this is not a high vacuum, in the true sense of the word, it is a sufficiently high vacuum to permit complete removal of dissolved gases for most metals, such as titanium, zirconium, tantalum, niobium and the like. It will also permit dissociation or volatilization of many oxides and nitrides particularly of the group V and group VI metals. At 18 there is schematically indicated a supply of metal powder or sponge and at 19 there is shown a conveyor means for feeding metal powder into the molten pool in the cold mold. In one embodiment of the invention, the cold mold 12 is preferably designed with a retractable mold stool 20 which can be gradually lowered by means of a feed screw 22 as the melting proceeds to permit the plane of the molten pool surface to remain substantially constant.

A cathode 24 for emitting electrons is positioned in a cathode chamber 26 communicating with the furnace chamber 10. This cathode 24 is preferably a concave tantalum or tungsten element and is arranged to be heated by a heater element 28. The cathode 24 has a focusing electrode 30 which, in combination with an accelerating anode 32 provides a high energy, focused beam 34 of electrons. In one preferred embodiment of the invention, the cathode 24 is at 20,000 volts negative with respect to the accelerating anode 32 which is at ground potential. The cathode chamber 26 is provided with a high vacuum pump 36 which maintains the cathode chamber at a pressure on the order of 0.01 micron Hg abs. The cathode chamber is isolated from the furnace chamber by a tube 38 containing several apertured partitions 40, 42 and 44 through which the focused electron beam 34 is directed into the furnace chamber and onto the furnace of the molten pool in the cold mold. Each aperture is preferably in the form of a cylinder which is coaxial with the electron beam and is slightly larger than the focused beam 34 of electrons to permit passage of the electron beam therethrough but to inhibit, as much as possible, the flow of gas from the furnace chamber 10 to the cathode chamber 26.

In one embodiment of the invention illustrated, there are three such apertures and three pumps. The first pump 36 provides for the maintenance of a very high vacuum (e.g. 1×10^{-5} mm. Hg abs.) in the cathode chamber 26. The second pump 46 maintains a pressure of about 0.1 micron (1×10^{-4} mm. Hg abs.) in the space between the partitions 40 and 42, while the third pump 48 maintains a pressure of about 1 micron between the partitions 42 and 44. The furnace chamber 10 is connected to the booster pump 16 which will maintain the pressure in 10 between 1 and 10 microns.

In addition to the elements enumerated above, the furnace includes a plurality of focusing coils for keeping the electron beam focused in a narrow beam for passage through the restricted openings in the partitions 40, 42 and 44. A suitable power supply 52 is provided for the focusing coils. A high voltage power supply 54 is connected to the elements of the electron emitter 24 and

beam forming anode 32. Suitable water connectors 56 are shown for supplying cooling water from a source thereof (not shown) to cool the mold 12 and the mold stool 20.

The present invention permits the holding of the molten pool for any desired time to permit purification of the melt. Thus, where the degassification or volatilization of impurities is dependent upon a definite time-temperature relationship, it is possible to achieve the desired time-temperature relationship by melting at a sufficiently slow rate. The invention also has the advantage that it eliminates the possibility of dangerous short circuits by gas discharge in the high voltage portion of the apparatus. This has the effect of greatly simplifying the design of the electrical system and lowers the cost of the high voltage power supply. The present invention also permits use of rather delicate cathode surfaces having materials of high electron emission without danger of spoiling such surfaces due to a pressure burst in the furnace. In this case a standard high-vacuum valve is preferably placed in tube 38 to maintain a high vacuum at all times in the vicinity of the cathode.

While one preferred embodiment of the invention has been described above, numerous modifications thereof can be made without departing from the scope of the invention. For example, more pumping chambers can be employed along the path of travel of the electron beam thereby decreasing the total volumetric capacity of the requisite pumps but increasing the number of such pumps. Similarly, the number of chambers can be decreased with increasing volumetric pumping requirements. Numerous other heating means and electron beam forming systems can be employed as well as other standard methods for feeding particular metal pieces such as sponge, chips, scrap, powder and the like.

Since certain changes may be made in the above apparatus without departing from the scope of the invention herein involved, it is intended that all matter contained in the above description or shown in the accompanying drawings be interpreted as illustrative and not in a limiting sense.

What is claimed is:

1. A furnace for melting gas-containing metal to produce gas-free metals, said furnace comprising a vacuum-tight furnace chamber, a cold mold in said chamber, means for evacuating said chamber to a free air pressure on the order of 1 micron Hg abs., a cathode, means for heating said cathode to produce thermal emission of electrons therefrom, means for accelerating said electrons and forming said electrons into a beam, said cathode being in a chamber which is isolated from said furnace chamber by at least one wall containing an aperture, means for evacuating said cathode chamber to a lower pressure than the furnace chamber to provide a low pressure zone, a magnetic focusing means creating a magnetic focusing field arranged to direct said electron beam from said low pressure zone through said aperture to the higher pressure zone, said magnetic field providing direction of said beam towards said cold mold with a force which is essentially free of voltage gradient and thus preventing electrical discharges despite the existence of an electrical-discharge-supporting pressure with a high degree of ion formation in the path of the beam adjacent said mold,

the distance between the nearest aperture through which the electron beam passes and the upper edge of the cold mold being substantially greater than the diameter of the cold mold to provide a large unobstructed volume for escape of gases from metal being melted in the cold mold, means for moving metal to be melted into position to be contacted by said electron beam within said cold mold, said vacuum pumping means associated with said cathode chamber having a sufficient pumping capacity to maintain said cathode chamber at a pressure less than .1 micron Hg abs. despite gases leaking through said aperture into the cathode chamber.

2. A furnace for melting gas-containing metal to produce gas-free metals, said furnace comprising a vacuum-tight furnace chamber, a cold mold in said chamber, means for evacuating said chamber to a free air pressure on the order of 1 micron Hg abs., a cathode, means for heating said cathode to produce thermal emission of electrons therefrom, means for accelerating said electrons and forming said electrons into a beam, said cathode being in a chamber which is isolated from said furnace chamber by at least one wall containing an aperture, means for evacuating said cathode chamber to a lower pressure than the furnace chamber to provide a low pressure zone, a first magnetic focusing means creating a first magnetic focusing field arranged to direct said electron beam from said low pressure zone through said aperture to a higher pressure zone, a second magnetic focusing means positioned to create a second magnetic focusing field on the higher pressure size of said first aperture, said second magnetic field providing direction of said beam through a second aperture in a second wall towards said cold mold with a force which is essentially free of voltage gradient and thus preventing electrical discharges despite the existence of an electrical-discharge-supporting pressure with a high degree of ion formation in the path of the beam adjacent said mold, the distance between the nearest aperture through which the electron beam passes and the upper edge of the cold mold being substantially greater than the diameter of the cold mold to provide a large unobstructed volume for escape of gases from metal being melted in the cold mold, means for moving metal to be melted into position to be contacted by said electron beam within said cold mold, said moving means being positioned between said second wall and said cold mold, said vacuum pumping means associated with said cathode chamber having a sufficient pumping capacity to maintain said cathode chamber at a pressure less than .1 micron Hg abs. despite gases leaking through said aperture into the cathode chamber.
